Inventor

GEORGE S. BRUSH,

By *Paul J. Fawcett* Attorney.

UNITED STATES PATENT OFFICE.

GEORGE SEIGFRIED BRUSH, OF ZANESVILLE, OHIO.

DESIGN FOR A CASING FOR RADIO SETS.

Application filed September 20, 1926. Serial No. 19,118. Term of patent 7 years.

To all whom it may concern:

Be it known that I, GEORGE SEIGFRIED BRUSH, a citizen of the United States, residing at Zanesville, in the county of Muskingum and State of Ohio, have invented a new, original, and ornamental Design for Casing for Radio Sets, of which the following is a specification, reference being had to the ac-

companying drawing, forming part thereof.

Fig. 1 is a front elevation of the casing for radio sets.

Fig. 2 is a side elevation.

I claim:

The ornamental design for a casing for radio sets as shown.

GEORGE SEIGFRIED BRUSH.
